UNITED STATES PATENT OFFICE.

WIRT D. RIAL, OF PONCA CITY, OKLAHOMA, ASSIGNOR TO MARLAND REFINING COMPANY, OF PONCA CITY, OKLAHOMA, A CORPORATION OF OKLAHOMA.

STILL.

1,390,386.

Specification of Letters Patent. Patented Sept. 13, 1921.

Application filed November 13, 1919. Serial No. 337,722.

To all whom it may concern:

Be it known that I, WIRT D. RIAL, a citizen of the United States, residing at Ponca City, in the county of Kay and State of Oklahoma, have invented certain new and useful Improvements in Stills, of which the following is a specification.

This invention relates to improvements in stills and more particularly to stills especially adapted for cracking hydro-carbons such as petroleum distillates although it is to be understood that, in its broader aspect, the invention is susceptible to various uses.

One of the objects of the present invention is to provide an improved still permitting a more automatic system of operation.

Another object is to provide a new and better means of scrubbing the bottom of the still.

20 A further object is to provide a still of the above character with various safety devices thereby making a more effective and safer apparatus for the treating of hydrocarbons.

25 A further object is to provide a semi-continuous re-run process which may be carried on under pressure and simultaneously continuously wash the bottom of the still, thereby keeping the same free from coke forming matter settling on the bottom of the still.

30 A further object is to provide means for relieving the pressure within the still and to equip the still with certain attachments and automatic valves whereby the pressure within the still is prevented from reaching 35 a dangerous degree and at the same time prevent loss by the escape of gases or the like through such relief devices.

These, and other objects which will appear obvious from the following specification, will be more clearly set forth and described in connection with the accompanying sheet of drawings wherein such parts of a system are shown as to fully understand the present invention.

45 In these drawings, wherein like reference characters denote corresponding parts throughout the several views.

Figure 1 is a semi-diagrammatic sectional elevational view of the complete system.

50 Fig. 2 is a semi-diagrammatic plan view of the system shown in Fig. 1, certain parts being shown in section or broken away for the sake of clearness.

Fig. 3 is a view taken on line 3—3. Fig. 1. 55 In these drawings 1 denotes the still

proper which is adapted to be filled with approximately 12,000 gallons of petroleum distillate at a temperature of 60° F. The still may be charged through a pipe 2 which is equipped with a swinging joint flanged into a manhole 3 during the charging, thereby to eliminate the possibility of igniting the gases by any sparks which might be caused by sudden impact of two metals. After the still is charged the pipe 2 is swung 60 back through the arc 4 out of the way and the manhole 3 securely closed. Heat is applied to the under side of the still as by means of a fire box 5 and oil burners 6 as diagrammatically shown.

At the same time a motor driven centrifugal pump 7 is started. This pump is especially adapted to handle hot oils at a temperature of approximately 800° F. and takes, by suction, out of the bottom of the still through a line 8, and discharges the same through a coil 9 connected with a discharge line 10 and branch pipes 11. The branch pipes 11 enter the coil through three headers from each of which branch several 75 smaller lateral pipes perforated along their under sides with small closely adjacent holes. By using three headers the liquid is equally distributed. The coil may be supported about two inches from the bottom of 80 the still as by means of chains 12. The line 10 is preferably supported from the top of the still by iron straps 13 welded to the interior of the surface of the still. By spraying the hot liquid against the bottom of the 85 still it is thoroughly scrubbed and the liquid kept in circulation, thus eliminating, to a large extent, the accumulation of coke forming matter which would otherwise collect on the bottom of the still and be dangerous in that it would keep the liquid from obtaining the proper amount of heat necessary in the cracking process. Any coke forming matter settling on the bottom of the 90 still would cause a hole to be burned in the fire sheet which condition would obviously be a serious menace to life and property.

95 The coil 9 is connected to the pipes 11 by means of flanges 14 which may be unbolted and the pipes 11 swung upwardly out of the 100 way when desired or they may also be provided with hooks secured to the top of the inside of the still whereby the coil 9 may be raised by a chain hoist, thereby allowing the 105 carbon deposit to be removed from the bot-

tom of the still periodically as is found necessary.

When the pressure on the inside of the still reaches a predetermined amount such 5 for example as 100 pounds per square inch, the pressure is automatically released by relief valve 15 which consists of a 1-inch valve and seat, both of monel metal, and a weight adapted to keep the valve closed until the 10 predetermined pressure is reached. In case of breakage of this valve 15 a second valve 16 may be closed and the pressure on the still regulated by a further valve 17.

In operation the vapor passes from the 15 still 1 through the line 18 to the towers 19, 20, 21 and 22 in each of which a certain amount of the vapor is condensed and trapped back to the still through a trap back line 23 connecting with the bottom of each tower. This line is always sealed with 20 liquid thereby preventing vapors from escaping therethrough. At the predetermined pressure the vapors in the tower 22 are released by the automatic valve 15 through a line 24 into a separating tower 25. This tower is equipped with shutters at the top and bottom to regulate the air passing through the tubes thereby regulating the condensation within this tower. The condensing separates the gasoline fractions from 25 the gas oil fractions which latter pass off as a liquid through a back trap line 26 into a coil in condenser box 27. The gasoline fractions pass off as a vapor through a vapor line 28 coming out near the top of tower 25 and leading into a separate and larger coil in the condenser box. The condenser box 27 is equipped with two separate coils placed 30 side by side, the back trap coil containing about one-third of the total cooling surface in the box and the coil for vapor containing about two thirds of the total cooling surface.

To take care of any excess pressure on the still which might be caused by negligence on 45 the part of the operator a large safety valve 29 is preferably placed on the tower 22 and set at 125 pounds per square inch. This valve also releases into tower 25 through the line 24 so that none of the vapors escaping from 50 either of the valves 15 or 29 are lost to the atmosphere. This positively eliminates any chances of fire which might be caused by releasing the vapors at this high temperature into the open air.

55 The process may be continued until a distillation of approximately 50% of the total charge has taken place. The still is then operated as a continuous process, being fed at the rate of five barrels per hour through a 60 separate feed line 30.

The tower 19 is divided into three horizontal compartments as indicated, the central compartment forming a chamber around vertical tubes, as shown, the chamber being 65 filled with the liquid passing through the line

30 while the vapors pass through the tubes. The liquid around the tubes in the tower 19 acts as a vapor heat interchanger whereby the liquid fed to the still is raised to a relatively high temperature. The still is continuous in operation as described, being recharged until an additional 12,000 gallons has been taken into the still, 50% of the inflowing liquid being vaporized.

When this continuous charging has been 75 completed the valve 17 and tower 22 are opened and the pressure on the still reduced to approximately 20 lbs. per square inch through the line 24 and tower 25. The residue or fuel oil in the still is pumped out 80 through line 31 which goes down to within an inch of the bottom of the still. This completes the cycle of operation which requires approximately seventy-two hours time.

I am aware that the prior art discloses certain machines and processes for treating or cracking hydro-carbons such as petroleum distillates, but not to my knowledge has there been used a process or apparatus for scrubbing the bottom of the still in the manner 90 herein shown and described nor have the stills been provided with the automatic safety devices adapted to relieve the pressure at a predetermined point without permitting the escape of the exhaust gases or vapors to the 95 atmosphere.

From the above it will be seen that the present apparatus provides a simple and practical means for accomplishing, among others, all of the objects and advantages here- 100 in set forth.

What I claim is:

1. In an apparatus of the character described, in combination, a still, means adapted to prevent substances settling on the bottom thereof and to afford unobstructed access to such bottom, said means comprising a pump, a circulating system connected with said pump, means within the still and adjustable toward and away from the bottom thereof and in circuit with said circulating system for discharging the liquid against the bottom of the still and adapted to be swung up away from said bottom to afford access thereto.

2. In an apparatus of the character described, in combination, a still, and means adapted to prevent substances settling on the bottom thereof comprising a pipe suspended from the upper part of the still carrying a plurality of headers flexibly supported closely adjacent the bottom of the still, and a plurality of lateral pipes having perforations on their under sides whereby the liquid within the still is drawn therefrom and discharged down through said perforations.

3. In an apparatus of the character described, in combination, a still and means adapted to prevent substances settling on the bottom thereof, comprising a central longi-

- tudinal pipe support from the upper part of the still, a plurality of branch pipes depending therefrom, said branch pipes each having a plurality of perforated lateral extensions and means for withdrawing the fluid within the still and discharging the same downwardly through said perforated lateral extensions thereby to scrub the bottom of the still.
- 5 10 4. In an apparatus of the character described, in combination, a still, a plurality of towers, a relief valve in one of said towers,
- and a plurality of valves exterior of said tower, all of said valves being adapted to discharge within the system and to open under 15 successively increasing pressure, and means for condensing the exhaust gases on the opening of any of said valves.
- In testimony whereof I affix my signature in the presence of two witnesses.

WIRT D. RIAL.
